Attorney.

UNITED STATES PATENT OFFICE.

ERNEST N. QUEEN, OF COMANCHE, TEXAS.

WASHING-MACHINE.

1,194,229.

Specification of Letters Patent.

Patented Aug. 8, 1916.

Application filed June 8, 1916. Serial No. 102,480.

To all whom it may concern:

Be it known that I, ERNEST N. QUEEN, a citizen of the United States, residing at Comanche, in the county of Comanche and 5 State of Texas, have invented certain new and useful Improvements in Washing-Machines; and I do hereby declare the following to be a full, clear, and exact description of the invention, such as will enable others 10 skilled in the art to which it appertains to make and use the same.

This invention relates to machines for washing clothes and other similar goods; and it consists in the novel construction and 15 combination of the parts hereinafter fully described and claimed.

In the drawings, Figure 1 is a side view of the washing machine, showing the water vessel partially in section. Fig. 2 is an end 20 view of the machine removed from the water vessel.

The water vessel or tub 2 is of any approved form and construction. A frame 3 is provided, and is secured in or over the 25 tub 2 in any convenient manner. The main driving shaft 4 is journaled in the lower part of the frame, and it has a fly-wheel and a crank-handle 5 on one end, or other suitable means for revolving it continuously 30 in one direction. A toothed pinion 6 is secured on the other end portion of the shaft 4. A countershaft 9 is also journaled in the frame, and a rocker-arm 7 having a toothed segment 8 is mounted loosely on the counter- 35 shaft 9. A toothed wheel 10 is secured on the countershaft, and is arranged in gear with the pinion 6. A crank 12 is secured to the pinion 6, and its pin engages with a radial slot 14 in the rocker-arm, so that the 40 rocker-arm and the toothed segment 8 are oscillated as the main shaft is revolved.

A series of lower washing rollers 15 is provided, and these rollers are secured on shafts 16 which are journaled in the frame 45 3. Toothed wheels 17 are secured on the shafts 16, and toothed idle wheels 18 are journaled on pins 19, and are arranged in gear with the wheels 17, so that the wheels and rollers all run in the same direction.

50 Pressing rollers 20 are provided and are arranged over the rollers 15. The rollers 20 have shafts 21 which are journaled in bearings 22 which are slidable vertically in slots 24 in the frame 3. Springs 25 are 55 provided for pressing the rollers 20 downwardly, and 36 are screws for adjusting the

pressure of the springs except those pertaining to the rear end rollers of the series. The rear end roller is provided with cams 26 secured on a shaft 27 which is journaled 60 in the frame 3. These cams are provided for greatly increasing the pressure of the springs so that the rear end rollers of the series may operate as a wringer before the clothes are discharged from the machine. 65 The straight arrows in Fig. 1 show the direction in which the clothes enter and leave the machine.

A ratchet wheel 28 is secured on the shaft 27, and 29 is a pivoted pawl which engages 70 with the teeth of the ratchet wheel, and prevents it from moving in the reverse direction after the upper roller has been arranged to wring the clothes. The cams 26 are operated by hand, and are not used until the 75 washing action is completed. The shaft of the lower end roller has a toothed pinion 30 splined to it, and 31 is a lever for moving the pinion 30 longitudinally on its shaft, and placing it in gear with the toothed 80 wheel 10 and the toothed segment 8 alternately, or at will. The lever 31 is pivoted on a pin 32 in a bracket carried by the frame, and 33 is a spring catch on the frame for holding the lever 31 in its extreme 85 positions.

When the clothes are entered between the rollers the rollers are all revolved in the direction of the curved arrows in the drawings. The pinion 30 is slid out of gear 90 with the wheel 10 before the clothes begin to pass out of the machine, and is placed in gear with the toothed segment 8. The rollers are then moved first in one direction and then in the other direction by the oscillating segment and rocker-arm, and the clothes are washed by the action of the rollers and water and soap. When the washing action is completed, the cams 26 are turned by hand to increase the spring pressure 100 on the last roller, and the pinion 30 is slid out of gear with the segment and into gear with the wheel 10, so that the surplus water is pressed out of the clothes, and the clothes are discharged at the rear end of the 105 machine.

What I claim is:

1. In a washing machine, washing rollers, a shaft for revolving one of the said rollers, a toothed pinion mounted to revolve with and slide longitudinally on the said shaft, a countershaft, a toothed wheel

secured on the countershaft, a toothed segment mounted loosely on the countershaft, means for oscillating the toothed segment and revolving the toothed wheel, and means 5 for placing the said pinion into and out of gear with the said segment and wheel.

2. In a washing machine, washing rollers, a shaft for revolving one of the said rollers, a toothed pinion mounted to revolve 10 with and slide longitudinally on the said shaft, a countershaft, a toothed wheel secured on the countershaft, a toothed segment mounted loosely on the countershaft and provided with a rocker-arm, a driving 15 pinion gearing into the said toothed wheel, a crank revolving with the driving pinion and engaging with the rocker-arm so that the toothed segment is oscillated as the toothed wheel is revolved, and means for 20 placing the slideable pinion into and out of gear with the said segment and wheel.

3. In a washing machine, a series of washing rollers arranged in pairs, driving mechanism operatively connecting the lower rollers of the pairs, springs for pressing the 25 upper rollers toward the lower rollers, pivoted cams for increasing the pressure of the springs of the discharge rollers at will, a shaft for driving the said lower rollers, a toothed pinion mounted to revolve with and 30 slide longitudinally on the said shaft, a countershaft, a toothed wheel secured on the countershaft, a toothed segment mounted loosely on the countershaft, means for oscillating the toothed segment and revolving 35 the toothed wheel, and means for placing the said pinion into and out of gear with the said segment and wheel.

In testimony whereof I have affixed my signature.

ERNEST N. QUEEN.
